UNITED STATES PATENT OFFICE.

GEORGE U. WILLS, OF PHILADELPHIA, PENNSYLVANIA.

DESIGN FOR A CRIBBAGE-BOARD.

SPECIFICATION forming part of Design No. 21,376, dated March 8, 1892.

Application filed October 15, 1891. Serial No. 408,846. Term of patent 14 years.

To all whom it may concern:

Be it known that I, GEORGE U. WILLS, a citizen of the United States, residing at Philadelphia, in the State of Pennsylvania, have invented and produced a new and original Design for Cribbage-Boards, of which the following is a specification, reference being had to the accompanying drawing, forming a part hereof.

- 10 Said drawing is a top or plan view of my design for a cribbage-board, showing the rectangular blocks, which contain the scoring-holes, and which latter form no part of the design itself.
- 15 The leading feature of my design consists in a cribbage-board of rectangular form having the ornamentation shown, comprising a

pair of disks, indicated, respectively, at A and A', arranged at points nearly intermediate between the longitudinal center of the board and the ends thereof, said disks being connected by scroll-work. The disks are, as will be seen by reference to the photograph, more prominent to the eye than the body of the scroll-work, and thus produce a characteristic effect.

I claim—

The design for a cribbage-board, as herein shown and described.

GEORGE U. WILLS.
